[57] CLAIM

The ornamental design for labelling apparatus, as shown.

DESCRIPTION

FIG. 1 is a side elevational view taken from the right side of the labelling apparatus embodying my new design;

FIG. 2 is an end elevational view taken from the left side of FIG. 1;

FIG. 3 is an end elevational view taken from the right side of FIG. 1;

FIG. 4 is a bottom plan view of the labelling apparatus embodying my new design;

FIG. 5 is a side elevational view illustrating the lefthand side of the labelling apparatus embodying my new design; and

FIG. 6 is a top plan view of the labelling apparatus embodying my new design.
